UNITED STATES PATENT OFFICE

143,623

DESIGN FOR A STOVE MAT

Edwin G. Pfursich, Chicago, Ill., assignor to Phoenix Table Mat Co., Chicago, Ill.

Application July 21, 1945, Serial No. 120,868

Term of patent 14 years

(Cl. D81—25)

To all whom it may concern:

Be it known that I, Edwin G. Pfursich, a citizen of the United States, residing at Chicago, in the county of Cook and State of Illinois, have invented a new, original, and ornamental Design for Stove Mats, of which the following is a specification, reference being had to the accompanying drawing, forming part thereof.

Fig. 1 is a top plan view of a stove mat, showing my new design; and

Fig. 2 is an edge view.

I claim:

The ornamental design for a stove mat, as shown.

EDWIN G. PFURSICH.
